ELECTRON DISCHARGE DEVICE

Clarence A. Boddie, Pittsburgh, Pa., assignor to
Westinghouse Electric & Manufacturing Com-
pany, a corporation of Pennsylvania

Application November 5, 1930, Serial No. 493,506

13 Claims. (Cl. 250—27.5)

My invention relates to electron-discharge devices and particularly to power tubes for generating high-frequency currents.

In the past, difficulty has been encountered in generating high-frequency currents by means of electron-discharge devices because of the capacity between the grid and plate electrodes. This difficulty has been caused by the fact that the vacuum tube was coupled to an oscillatory circuit which included lumped inductance and lumped capacity, the lumped capacity being connected across the grid and plate electrodes. Since the frequency at which the vacuum tube would oscillate was increased by decreasing the value of the lumped capacity, the grid-plate capacity determined the maximum frequency at which energy could be generated. With this type of high-frequency generator, therefore, the amount that the frequency of the current generated could be increased was limited because of the mechanical difficulties encountered in increasing the spacing between the grid and the plate to reduce the grid-plate capacity.

An object of my invention is to provide an electron-discharge device of the above-mentioned type which is so designed that the grid-plate capacity imposes no limitation upon the frequency of the current that is generated.

More particularly, an object of my invention is to provide a vacuum tube in which the grid and plate elements form a portion of a transmission line and in which the frequency of the generated current is determined by the characteristics of said line.

A further object of my invention is to provide a structure of the above-mentioned type which has the desired electrical characteristics and which, at the same time, is so designed mechanically that it conforms to the preferred practice in constructing large power tubes.

In practicing my invention, I employ two similar three-element vacuum tubes, each tube comprising an evacuated envelope having a metal wall which acts as an anode. The anodes of the vacuum tubes are electrically connected by means of a metal pipe. The control electrodes of the vacuum tubes are also electrically connected by means of a second metal pipe. Since the outer pipe has a larger diameter than that of the anodes in order that it may extend over the glass end or blank of the tube, the diameter of the inner pipe is enlarged at the point where it extends beyond the glass blank. In this way, the grid and plate electrodes and the two pipes form a transmission line which consists of two

concentric tubes the diameters of which have the same ratio throughout the length of the line. This forms a transmission line which has uniformly distributed inductance and capacity.

The outer pipe has a larger diameter than the anodes for mechanical reasons, while the inner pipe has a larger diameter than the control electrodes in order that the portion of the line which is formed by the two pipes may have an impedance which matches the impedance of that portion of the line which is formed by the grids and plates. The distance from the outer end of one anode to the outer end of the other anode determines the length of the standing wave which may be generated and, therefore, the frequency of the current which is generated by the oscillator.

Other features and advantages of my invention will appear from the following description, taken in connection with the accompanying drawings, in which,

Fig. 1 is a diagrammatic view, in longitudinal section, of a vacuum-tube oscillator constructed in accordance with my invention;

Fig. 2 is a diagrammatic view of the electrical connections employed in my invention.

Fig. 3 is a diagrammatic view of an oscillator to aid in explaining the operation of the circuit shown in Fig. 2;

Fig. 4 is a view, in longitudinal section, of the upper end of one of the vacuum tubes which are employed in the oscillator illustrated in Fig. 1;

Fig. 5 is a view, in longitudinal section, of the lower end of the vacuum tube shown in Fig. 4 and of a portion of the pipes employed to connect the two vacuum tubes;

Fig. 6 is a view, in longitudinal section, of a portion of the pipes which are employed in connecting the vacuum tubes;

Fig. 7 is a view, in lateral section, taken on the line VII—VII of Fig. 4, and

Fig. 8 is a view of the upper end of the tube shown in Fig. 4.

Referring to Fig. 1, the apparatus comprises two similar three-electrode vacuum tubes. Each vacuum tube comprises an evacuated envelope 10 having an outer metallic wall 11 which acts as the anode. The metallic wall 11 is closed at each end by means of glass blanks 12 and 13. The anode 11 is provided with a water-cooling jacket 100 14. The control electrode 15 is supported, at one end, by means of the glass blank 13 while the filament 16 is supported from the glass blank 12. The anodes 11 of the two tubes are connected together by means of a cylindrical metallic pipe 110

17 which is supported at each end by means of the anode cooling jacket 14. Conductors 18 and 19 extend from the pipe 17 through openings in a metallic casing 20 which shields the apparatus 5 to prevent radiation from the generator itself.

A circular metallic pipe 21 is positioned within the outer pipe 17 and supported, at each end, by means of a control electrode 15. A grid conductor 22 extends from the pipe 21 through openings 10 in the pipe 17 and the casing 20.

Referring to Figs 4 to 8, the glass blank 12 includes three re-entrant portions 23, 24, and 25, in which are sealed metallic rods 26, 27 and 28, respectively. These rods are brought near to, but 15 not in contact with, each other at the middle of the tube as shown in Fig. 4. The rod 28, which extends from the re-entrant portion 25, is hidden back of re-entrant portion 24 in Fig. 4. The rod 26 supports a rod 26' which is centrally located 20 in the tube.

The rods 27 and 28 support the filament wires 29 and act as the filament lead-in conductors. The filament wires 29 are supported from the rods 27 and 28 by means of heavy wires 27' and 28' 25 secured to rods 27 and 28 by means of clamps or sleeves 30.

The lower ends of the filaments 29 are supported by means of metal hooks 31 which are attached to the lower end of the rod 26'.

30 In practice, six or eight filaments, in parallel, are employed instead of only the two which are illustrated.

It will be noted that a large portion of the middle section of the tube has been cut away in 35 Figs. 4 and 5 in order to show the tube structure more clearly.

An electrostatic shield 32 is clamped to each of the rods 26, 27, and 28 to protect the seals.

The grid 15 comprises a plurality of metallic 40 rods 33 which are arranged in the form of a circular cage and which are held in position by means of metallic rings 34. The grid is supported at the end of the tube opposite the filament support by means of a metal thimble 35 which has 45 its edges sealed to the lower glass blank 13.

The thimble 35 is externally threaded to hold an electrostatic shield 36 in position over the seal. The thimble is internally threaded to provide a support for one end of the pipe 21'.

50 The anode 11 may be provided with any suitable cooling means. In the apparatus illustrated, the cooling means comprises an outer wall 14 which is in the form of a circular pipe supported at its ends by means of annular metallic members

55 38 and 39. The annular members 38 and 39 are held in screw-threaded relation to the anode 11. The joint between the upper end of the wall 14 and the annular member 38 is made liquid tight by means of a gasket 40 which is clamped between

60 the end of the wall 14 and a flanged ring 41. The ring 41 fits over the annular member 38 and is split in halves.

The joint between the lower end of the wall 14 and the annular member 39 is made liquid 65 tight by means of a gasket 42 which is clamped between the wall 14 and a flanged ring 43. The flanged ring 43 is slidably mounted on the annular member 39 to prevent breakage of parts caused by their unequal expansion when heated. An inlet and an outlet for the cooling fluid are provided by the pipes 44 and 45.

An electrostatic shield 46 is bolted to the flanged ring 41. The anode 11 is internally threaded at each end in order to support electrostatic shields 70 47 and 48.

Each end of the outer pipe 17, which acts as a section of a transmission line and which electrically connects the anodes of the two vacuum tubes, is bolted to one of the annular metallic members 38 and 39. It will be noted that the end of the pipe 17 is split to make it more readily fit over the supporting member 39.

The pipe 21' is increased in diameter, in effect, by terminating it at a point just beyond the glass blank 13 and by flexibly connecting thereto a pipe 21 of larger diameter. The pipe 21 is held in position at each end by means of a group of three quartz tubes 49 (Fig. 6). A good electrical contact between the pipes 21' and 21 is made certain by means of electrical conductors 50 which are clamped to the pipe 21' and held by means of soldering and a number of turns of wire on the larger pipe 21.

In order to match the impedance of the portion of the line formed by the vacuum-tube electrodes 11 and 15 with the impedance of the line formed by the pipes 17 and 21 connecting the two vacuum tubes, the parts are so proportioned that the ratio of the external diameter of the grid cage 15 to the internal diameter of the anode 11 130 is substantially the same as the ratio of the external diameter of the pipe 21 to the internal diameter of the pipe 17. With this design, the two line portions mentioned above have the same characteristic impedance, characteristic impedance being defined as the value

$$\frac{L}{C}$$

where L is the inductance and C the capacity 110 per unit length of the line.

While the structure of the vacuum tube illustrated is such that there is necessarily a slight impedance irregularity between the grid 15 and the enlarged portion 21 of the inner pipe, this irregularity does not seriously affect the operation of the system, and the vacuum-tube electrodes and the pipes 17 and 21 will act as a line having uniformly distributed capacity and inductance.

Referring to Fig. 5, the glass blank 13 and the grid-supporting thimble 35 are cooled by means of a current of air which enters through the pipe 51 and, after being deflected by the baffle 52, circulates around the blank 13, through the openings 53 in the pipe 21', through the opening 54 in the 125 end of a baffle tube 55, and through the pipes 21' and 21. At the other end of the outer pipe 17, air is blown around the glass blank 13 of the other tube in a similar manner. The connection between the pipes 21 and 21' is made air tight by 130 means of rings 56.

The air leaves the inner pipe 21 through the quartz tube 49 shown in Fig. 6. The inner end of each tube 49 is supported by a block 57 and in alignment with an opening 49'. The outer end of the tube 49 is supported by a plug 58 which is held in screw-threaded relation to a short length of pipe 59 welded to the pipe 17. A similar group of quartz-tube outlets is provided for the air blown in from the other end of the pipe 17.

In order to make the inner pipes 21' and 21 accessible to facilitate assembly, the top half of each end of the pipe 17 is cut free from the rest of the pipe to form a removable section which is held in position by means of a cover plate 60. The cover plate is held to the main section of the pipe 17 by means of screws 61 and is soldered to the top half pipe 17 to form an electrical connection.

Referring to Fig. 2, the cathode 16 of each tube

is preferably heated from an alternating-current source by means of a transformer 62 which has the mid-point of its secondary grounded. Radio-frequency choke coils 63 are preferably inserted

5 in the filament leads. The plate voltage may be supplied from any high-voltage direct-current source 64 and, although it may be connected to the system at any point on the anodes 11 or outer pipe or line 17, it is preferably applied at the middle of the pipe. This point of application is preferred when a line one-half wave length long is utilized, because the voltage is then applied at the node of the standing voltage wave, as indicated by the dotted line 65. In any case, a 10 choke coil 66 is preferably inserted in the high-voltage conductor 18.

15 The grids 15 are preferably connected to ground through a conductor 22, choke coil 67 and a condenser 68 and grid leak 69. As in the case of the connection of the plate system to the high-voltage supply, the grid system may be connected to ground at any point but it is preferably connected to ground at the middle of the inner pipe where the node of the standing wave is located.

20 25 A radiating system, which may comprise an antenna 70 and counterpoise 71 and tuning inductances 72 and 73, connected through a conductor 19' to a high-voltage point on the pipe or conductor 17. A radiating system of this character is described in U. S. Patent 1,652,516 issued to Westinghouse Electric & Manufacturing Company on December 13, 1927 upon an application filed by F. Conrad.

30 35 The operation of my high-frequency generator is analogous to the operation of the well known circuit illustrated in Fig. 3. In Fig. 3, the generator comprises a three-electrode vacuum tube having a grid 74, a plate 75 and a filament 76. The frequency at which the system oscillates is determined by the natural period of an oscillatory circuit consisting of an inductance coil 77 and a condenser 78 connected in parallel thereto. The filament 76 and the mid point of the inductance coil 77 are grounded. The grid 74 is connected 40 45 to the inductance coil 77 at one side of the grounded point, and the plate 75 is connected to the inductance coil 77 on the opposite side of the grounded point. The necessary positive potential is supplied to the plate through a choke coil 50 55 79.

55 60 In the circuit shown in Fig. 2, the distributed inductance and capacity of the line formed by the grids 15 and the pipe 21 and the plates 11 and the pipe 17, replace the lumped inductance 77 and the capacity 78 of the circuit shown in Fig. 3. The oscillatory circuit shown in Fig. 2 does not have the direct connection to ground at any point but the system is allowed to have a floating ground potential.

65 70 75 Since a vacuum tube is a high impedance device, it is necessary, for efficient operation, that the tube shall work into a circuit having a high impedance, preferably an impedance of the order of that of the output of the vacuum tube. A transmission line, either a quarter-wave length or a half-wave length would give the required high impedance, but, in the case of a line a quarter wave length, it would be necessary to short circuit the end of the line. Since this would require the use of a large condenser, a line which is one-half wave length is preferred.

75 The system may be caused to generate higher frequencies than those indicated above by connecting an impedance unit across a certain portion of the transmission line, that is, between the

80 pipes 17 and 21. As shown in Fig. 2, this may be accomplished by closing the switch 80 to connect the resistance unit 81 across the conductors 17 and 21.

85 A standing voltage wave will then be set up on the line as indicated by the dotted line 82, a node being located at the point where the resistance unit 81 connects the conductors together. This result is based on the principle that an oscillation generator will oscillate at that frequency for which the system losses are the lowest.

90 95 Various modifications may be made in my invention without departing from the spirit and scope thereof, and I desire, therefore, that only such limitations shall be placed thereon as are shown by the prior art and are set forth in the appended claims.

I claim as my invention:

95 100 105 1. An electron-discharge device including an anode and a control electrode, two conductors therein having uniformly distributed inductance and capacity, and means connecting said anode to one of said conductors and said control electrode to the other of said conductors, the characteristic impedance of the line formed by said anode and said grid being substantially equal to the characteristic impedance of the line formed by said conductors.

110 115 120 125 2. A high-frequency generator comprising an electron-discharge tube having an anode and a control electrode which form a section of a transmission line therein having uniformly distributed capacity and inductance, a second section of a transmission line having uniformly distributed capacity and inductance of unit values different from those of the first said section, means conductively connecting said transmission line sections, the characteristic impedances of said sections being substantially equal.

130 135 140 145 3. An electron-discharge device including an evacuated vessel enclosing a cathode and having a metallic wall which acts as an anode, a member of insulating material sealing one end of said metallic wall, said member having larger lateral external dimensions than said wall, a control electrode positioned within said vessel, a metallic tube surrounding said member and connected to said wall, and a second metallic tube positioned within said first-named tube and said insulating member and connected to said control electrode.

150 155 160 165 4. A high-frequency generator comprising two electron discharge devices, each device including an evacuated vessel having a metallic wall which acts as an anode and a member of insulating material sealed to one end of said wall, said member having larger lateral external dimensions than said wall, a cathode and a control electrode positioned within said vessel, a metallic tube surrounding said control electrode and connected to said wall, and a second metallic tube positioned within said first-named tube and said insulating member and connected to said control electrode, the first-named metallic tubes of said devices being connected together at their free ends, and said second tubes of said devices being connected together at their free ends.

170 175 180 185 5. A high-frequency generator comprising two electron discharge devices, each device including an evacuated vessel enclosing a cathode and having a metallic wall which acts as an anode and a member of insulating material sealed to one end of said wall, said member having larger lateral external dimensions than said wall, a control electrode positioned within said vessel, a metallic tube surrounding said member and connected to

said wall, and a second metallic tube positioned within said first-named tube and said insulating member and connected to said control electrode, the spacing between said tubes being decreased 5 at a point immediately beyond said insulating member.

6. A high-frequency generator comprising an evacuated vessel having a metallic wall which acts as an anode, a control electrode and a cathode positioned within said vessel, said anode and said control electrode forming a portion of a line having substantially uniformly distributed inductance and capacity, two electrical conductors forming the other portion of said line, said anode 10 being connected to one of said conductors and said control electrode being connected to the other of said conductors.

7. An electron discharge device including an evacuated vessel enclosing a cathode and having a metal wall which acts as an anode, a control electrode positioned within said vessel, a metallic tube connected to said anode, and a metallic tube positioned within said first tube and connected to said control electrode, said tubes and electrodes 20 forming an oscillating system, and means for connecting a source of direct current potential to said anode at a point one-quarter wave length from the end of said system.

8. An electron discharge device including an evacuated vessel enclosing a cathode and having a cylindrical metallic wall which acts as an anode, a member of insulating material sealing one end of said metallic wall, said member having a larger diameter than said wall, a control electrode of circular cross-section positioned within said vessel, a cylindrical metallic tube surrounding said member and connected to said wall, and a second cylindrical metallic tube positioned within said first-named tube and said insulating member and connected to said control electrode, the ratio of the diameter of said first-named tube to the diameter of said second tube 30 at the region immediately beyond said insulating member being substantially equal to the ratio 40 of the diameter of said anode to the diameter of said control electrode.

9. An oscillation generator including conductors having substantially uniformly distributed capacity and inductance whereby a standing wave may be formed thereon, means for controlling the frequency of the energy generated 50 which comprises a resistor connected between said conductors at a point where a voltage node will be formed.

55 10. An oscillation generator including con-

ductors having substantially uniformly distributed capacity and inductance whereby a standing wave may be formed thereon, means for forming a standing wave on said conductors which has a wave length different from the fundamental wave 80 length of said conductors, said means comprising an impedance unit connected between said conductors at a point where a voltage node will be formed.

11. An electron-discharge device including an evacuated vessel enclosing a cathode and having a metallic wall which acts as an anode, a member of insulating material sealing one end of said metallic wall, said member having larger lateral external dimensions than said wall, a control electrode positioned within said vessel, a metallic tube surrounding said member and connected to said wall, and a second metallic tube positioned within said first-named tube and said insulating member and connected to said control electrode, the spacing between said tubes being decreased 85 90 at a point immediately beyond said insulating member.

12. An electron-discharge device including an evacuated vessel enclosing a cathode and having a metallic wall which acts as an anode, a member of insulating material sealing one end of said metallic wall, said member having larger lateral external dimensions than said wall, a control electrode positioned within said vessel, a metallic 100 105 tube surrounding said member and connected to said wall, and a second metallic tube positioned within said first-named tube and said insulating member and connected to said control electrode, the characteristic impedance of the portion of the line formed by said tubes being substantially the same as that of the portion of the line formed by said anode and said control electrode.

13. A high-frequency generator comprising an evacuated vessel having a metallic wall which acts as an anode, a control electrode and a cathode positioned within said vessel, said anode and said control electrode forming a portion of a line having substantially uniformly distributed inductance and capacity, two electrical conductors forming the other portion of said line, said anode being connected to one of said conductors and said control electrode being connected to the other of said conductors, said other portion of 115 120 125 said line having a characteristic impedance which is substantially equal to the characteristic impedance of said first-named portion of said line.
